NOAH DICE, OF XENIA, INDIANA.

Letters Patent No. 98,572, dated January 4, 1870.

IMPROVED BUCKLE.

The Schedule referred to in these Letters Patent and making part of the same.

To all whom it may concern:

Be it known that I, NOAH DICE, of Xenia, in the county of Miami, and State of Indiana, have invented an Improved Buckle; and I do hereby declare that the following is a full, clear, and exact description thereof, reference being had to the annexed drawings, making part of this specification, in which—

Figure 1 is a top view,

Figure 2 is a bottom view, and

Figure 3 is a section on line $z z$ of fig 1.

The same letters are used to designate identical parts in the several figures.

My invention relates to a buckle, more particularly designed to be used on stirrup-straps, to lengthen or shorten the same; and

My improvement consists in the construction of its frame, and the arrangement of the tongue therein, as hereinafter more fully set forth.

To enable those skilled in the art to make and use my invention, I will proceed to describe its construction and operation.

A, in the drawings, represents the frame of a buckle, made of cast-iron or other suitable material, and consisting of a rectangular piece of metal, of sufficient thickness to have a groove, a , formed in its upper surface, wherein the tongue is to be placed.

To make the frame as light as possible, its sides and one end are bevelled, as shown in figs. 1 and 3, leaving its upper surface just wide enough for the groove or recess.

Upon its under surface it is provided with strips, a' , running along its sides, and loops, A' , formed by

cross-bars extending across from strip to strip; as shown in fig. 2, all cast in one piece with the frame.

A^2 is another loop, formed upon one end, for the purpose of receiving that end of the strap which is to be permanently secured to it.

B represents the tongue, provided with a pin or stud, B' , at one end. It is to be formed as shown in fig. 3, so that when it is placed in the recess and pivoted in the frame, it can be held by the action of the spring C, in such a position that its upper surface is flush with the upper surface of the frame A, and its stud projects through a perforation therein, a sufficient distance to penetrate a strap to be confined in the device.

By depressing the end laying upon the spring, the stud is retracted so as to release the strap.

The tongue is of nearly the same length and width as the recess a , so as to entirely cover the same.

Having thus described my invention, what I claim, and desire to secure by Letters Patent, is—

The buckle herein described, consisting of the frame A, tongue B, and spring C, all constructed and arranged with reference to one another, as set forth.

In testimony whereof, I have signed my name to this specification, in the presence of two subscribing witnesses.

NOAH DICE.

Witnesses:

WM. H. TURNER,
GEORGE DARE.
